NECKTIE

Harry Kahn, New Bern, N. C., assignor, by mesne assignments, to Ready Made Neckwear Corporation, a corporation of New Jersey

Application September 15, 1937, Serial No. 164,071

2 Claims. (Cl. 2—155)

This invention relates to neckties of the type in which a knot is formed and portions of the tie are caused to slide with respect to one another in adapting the tie to the neck of the wearer. 5 An example of such ties is the so-called "four-in-hand."

One of the features of the present invention is the provision of a tie structure by which a knot may be formed, and thereafter the tie may be 10 put on and taken off without disassembly of the knot, and without creasing or rumpling visible portions of the tie.

Another feature of the invention resides in the construction and arrangement of parts whereby 15 strength and convenience are assured.

With these and other features as objects in view, as will appear in the course of the following specification and claims, illustrative forms of practicing the invention are set out on the 20 accompanying drawing, in which:

Fig. 1 is a view of the tie in the assembled condition in which it is worn.

Figs. 2, 3 and 4 are successive diagrammatic views of fragments of tie portions, showing one 25 manner of assembling and securing the parts.

Fig. 5 is an enlarged perspective view, showing a preferred manner of forming the knot in the tie.

Fig. 6 is a substantially horizontal view of the 30 knot, indicating the relationship of the successive layers of material.

Fig. 7 is a fragmentary view corresponding to Fig. 4, of a modified manner of assembling the parts.

As shown in Fig. 1, the tie assembly is comprised of two sections, one of which may be called the knot-forming section K while the other may be called the slip section S. Each of these sections includes a portion 10k, 10s intended 35 to pass around a part of the neck of the wearer, and each also includes a drop or tag section 11k, 11s which falls, in the usual manner of a four-in-hand tie, downward from the knot formed at the wearer's throat. It is usually preferred to have the tag section 11k wider than the section 11s, so that it substantially covers and conceals the other while worn.

At the ends of the neck sections 10k, 10s, these 50 are provided with detachable connections 12 which are illustrated as being of hook-and-eye type, and are preferably formed of non-corrosive sheet metal and to have a width not greater than the adjacent ends of the sections 10k, 10s, and 55 having a thickness which is not substantially

greater than the thickness of the adjacent parts of such sections.

One manner of constructing a tie of this type is illustrated in Figs. 2, 3 and 4.

In Fig. 2, the exposed portion of the tie is illustrated as formed of fabric which is folded and sewed to form a tube 15, the sewing being accomplished while the fabric is inside-out. A reinforcing strip 16, shorter than the length of the section to be formed by the fabric tube 15 10 but of sufficient length so that a pulling of the section during the forming of the knot or the adjustment of the tie in the collar will be transmitted along the reinforcing or stiffening strip, is formed of burlap or like material capable of 15 resisting stretching. A fabric loop 17 is passed through one section of the detachable fastening means 12 and its ends brought down upon the end of the reinforcing member 16, and secured fixedly thereto as by the stitching 18. The fabric tubing 15 is now slipped over the detachable securing means 12 so that it laps onto the loop 17 and is then secured thereto (Fig. 3) by the further stitching 19. The fabric tube 15 is now reversed or turned right-side-out, as indicated 20 by the dotted lines 15x in Fig. 3, until the detachable securing means and a short bight portion of the loop 17 is exposed (Fig. 4).

It is preferred to complete the finish of the article, adjacent the detachable securing means, 30 by a further line of stitches 20 which are applied after the parts have been brought into the position of Fig. 4.

It will be understood that the two sections may be formed in the same general manner, except that one section receives the eye portion 12e of the illustrated detachable securing means, while the other section receives the hook portion 12h.

It is preferred to vend the ties with the knots preformed therein, as a particular form of knot has been found advantageous in permitting the proper slipping and adjustment of the sections while being applied around the neck. This knot is illustrated in Figs. 1, 5 and 6. To form it, the 45 neck section 10s of the slip portion of the necktie is held substantially straight, and the knot portion of the tie is passed around it, to form a first turn 20k, and then passed a second time around the turn 20k already formed to provide 50 the exposed facing layer 21k, and then brought beneath and behind the section 10s, and then over this section and downward in front of the slip portion S, so that the upper portion of the tag end 11k which is present within the layers 55

20k, 21k embraces or substantially surrounds (Fig. 6) the slip portion of the tie, within the knot, while the tag end 11k is brought downward in the usual manner. The portion of the knot 5 section 11k which is located within the knot layers 20k, 21k, is then conformed so that it fits smoothly around the slip section within the said layers, and then the parts are drawn tight to give a form to the knot as indicated in Fig. 1.

10 This positioning of the wider knot section 11k to embrace the slip section permits easy slippage of the parts relative to one another during adjustment, and avoids the use of such stresses as would wrinkle or distort the knot; and yet assures a sufficiency of friction to prevent accidental slippage at the knot while the tie is being worn.

In the modified form of construction shown in Fig. 7, the loop 17m is placed externally over the 20 fabric tubing 15 while the latter is right-side-out, and surrounds the reenforcing member 16. The parts are then secured by stitches 18m which fixedly connect the loop 17m with the reenforcing member 16, so that the stresses during adjustment of the tie are transmitted through the reenforcing member, as before, without straining and causing puckering or wrinkling in the outer tubular fabric section 15.

It will be noted that the form of Fig. 7 may be 30 made by cutting a normal four-in-hand tie and applying the loops 17m to the ends thereof.

The assembled tie can be put on and worn with a soft collar by raising the collar band and passing the sections 10s, 10k around the neck and 35 engaging the detachable securing means 12 at the back of the neck. The collar band is then turned down and adjusted to proper position; and by a light upward pressure upon the knot and a downward pull on the tag end 11s, the proper adjustment of length is effected, and likewise a displacement of the knot to one side or the other will properly center it at the break of the collar.

The tie may be removed by pulling the knot downward to afford slack in the neck section, 45 whereupon the detachable securing means 12 may be separated and the tie removed. It will be noted that it is unnecessary to release the knot for this purpose.

If the tie becomes soiled, however, it is possible 50 to open the knot and clean the tie, and then reform the knot either before applying the tie, or upon the neck of the wearer after the detachable securing means have been previously engaged.

It will be noted that the tie may be made of 55 various fabrics or combinations of fabrics, such as silk, cotton, woolen, artificial silk, or the like, which may be simple or lined fabrics; and that

the reenforcing member may be dispensed with if the fabric itself is resistant to stretching.

It is obvious that further changes may be made in the practice of the invention without departing from the scope of the appended claims. 5

I claim:

1. A necktie comprising two sections, each of which is comprised externally of a tubular structure of dress fabric and has a non-stretching internal reinforcing member, one said section being constructed and arranged to be looped around the other for forming the tie knot and for permitting the other to slide relatively in the knot, detachable connecting means for joining the sections, the dress fabric tubes being turned inward 15 at the connectable ends of the sections and the connecting means including flexible securing members which pass within said inturned portions of the fabric, and means for each section for fixedly securing the fabric, reinforcing member and securing member together, said internal reinforcing members extending from the detachable connecting means toward the end of the corresponding section for a distance sufficient to extend through the knot and sliding portions and 20 permit engagement thereof when the dress fabric tubes are grasped for exerting pulls along the lengths of the sections, whereby the reinforcing members are effective to prevent stresses in the 25 dress fabric material. 30

2. As an article of manufacture, a pre-tied necktie comprising first and second sections having external dress fabric members of tubular form, said sections each including an internal stiffening member for resisting stretching of the 35 section during pulls therealong, each section having tying and neck portions, interengaging detachable fastening means at the ends of the neck portions for transferring pulls between the sections without stretching when said means are engaged together, the tying portion of one section 40 having a knot formed therein, said knot embracing the tying portion of the other section and being slidable therealong without deformation of the knot for permitting the formation of slack 45 incident to effecting release or connection of said detachable fastening means and the adjustment of the knot on the wearer's collar, said stiffening members being fixedly connected to the fastening means and extending from the fastening means 50 and within the dress fabric members to points substantially below the knot for transmitting pulls along the lengths of the sections independently of the dress fabric members during the adjustment of the knot on the wearer's collar. 55

HARRY KAHN.
